ALBERT F. KERSTING, OF SPRING HILL, ALABAMA, ASSIGNOR OF ONE-HALF TO
LAZENBY C. HAMLINK, OF CLEVELAND, OHIO.

METHOD OF AND APPARATUS FOR MANUFACTURING GAS.

1,420,041.

Specification of Letters Patent. Patented June 20, 1922.

Application filed May 2, 1919. Serial No. 294,220.

To all whom it may concern:

Be it known that I, ALBERT F. KERSTING, a citizen of the United States, resident of Spring Hill, county of Mobile, and State of Alabama, have invented new and useful Improvements in Methods of and Apparatus for Manufacturing Gas, of which the following is a specification, the principle of the invention being herein explained and the best mode in which I have contemplated applying that principle, so as to distinguish it from other inventions.

My invention relates to methods of, and apparatus for, manufacturing gas; and particularly to improvements in the processes and apparatus for obtaining gas by the destructive distillation of coal. My improved process and apparatus is designed to procure, from the same amount of raw material previously used, a largely increased amount of gas of equal quality.

The annexed drawings and the following description set forth in detail certain steps and means illustrating and embodying my invention, such disclosed steps and means constituting, however, but one of the various methods by which my improved process may be carried out and but one of the exemplifications of the means that may be employed.

30 In said annexed drawings:

Figure 1 presents an end elevation of a retort bench, taken from the charging side which is also the side, in the type of apparatus herewith disclosed, upon which I locate my improved gas transfer means.

Figure 2 represents a broken vertical longitudinal section, taken in the plane indicated by the line II—II, Figure 1;

Figure 3 represents a broken vertical longitudinal section of a common stop end retort equipped with my improved apparatus, this illustration showing the use with only one vertical tier of retorts;

Figure 4 represents a rear elevation of the apparatus shown in Figure 3.

My improved process is based upon a correction and improvement in the following conditions attendant upon the manufacture of coal gas. The gas retorts are intermittently recharged with coal so that the volume of gas evolved and its heating value varies from time to time. The volume is relatively greater and the heating value relatively higher during the early stages of the car-

bonizing period. Inasmuch as the heating conditions necessary to fix the gas are constant for the area exposed, it results that the gas evolved during the early stages of a carbonizing period is not sufficiently fixed into permanent gas so that a condensation of a large percent of the hydrocarbon vapors, and their loss in the form of tar, result. On the contrary, during the last stages of any carbonizing period, the gases are exposed to too much fixation, resulting in their decomposition and the formation of free carbon. My process is designed to equalize these conditions and result in sufficiently fixed gas during the early stages and gas which is not over-fixed in the later stages of carbonization. The result is a large increase in gas of equal quality, such an increase as thirty percent (30%), I have found in actual practice. Furthermore, my improved process results in keeping the offtake pipes very clear of decomposed hydrocarbons which, in the processes heretofore used, tended to settle in said pipes in the form of carbon and thick tarry matter. These deposits in the offtake pipes have made it necessary to steam the retorts heretofore, or to run ammoniacal liquor through the medium of complex pumps, through the offtake pipes, or to clean the same in some other expensive manner and with a corresponding loss in production.

According to the usual practice, my process is so carried out that the coal retorts in each group shall be re-charged in sequence, the carbonizing periods being divided into equal time intervals. I have disclosed a bench of these retorts in Figures 1 and 2, the same being parallel vertical tiers of horizontally disposed retorts 4, 4' and 4'', the charging side of the same being upon the left of Figure 2, and the offtake side of the same upon the right of said figure. These several retorts are subjected to the same furnace conditions; there being no differential heating by the furnace of charges which are in different stages of carbonization. A gas transfer or equalizing means forming part of my invention is disposed upon the charging side of the retort bench, in the form of apparatus disclosed in said figures, although it would be possible to locate said means upon either side of the retort bench, provided the same are at the end opposite the regular final gas offtake end. Furthermore,

my improved process is equally practicable in operation in connection with the common stop end retort which has only one mouth-piece for charging and discharging same, as 5 in this case it is possible to penetrate the back wall of the retort as plainly shown in Figures 3 and 4. This application of my invention will be hereinafter described in detail. My invention is also applicable to the modern 10 coke oven with its gas offtake at the top. Said gas transfer means consist of a vertical transfer pipe 1 connected by the gas conduits 2 to the several retort-charging mouthpieces 3, 3' and 3''. In the form of construction 15 illustrated in Figures 1 and 2 this transfer pipe 1 is located between two parallel tiers of retorts 4, 4' and 4'', but in the case of one tier it is located laterally thereof, as shown in Figures 3 and 4, and any other suitable 20 arrangement serves the purpose. The several gas conduits are provided with valves 5 adapted to be actuated by a quarter turn of suitable levers 6. Hand holes are provided in the front face of the transfer pipe 25 casting 1 and provided with cover plates 7, for the purpose of access to the valves 5. Steam jet pipes 8 and 8' intersect the casting 1 and are used for the purpose of aiding the transfer of the gas, if the same is necessary 30 or desirable. Furthermore, the steaming by means of the pipes 8 and 8' also increases the yield of gas, increasing the total B. T. U.'s per pound of charge, as is well known.

My improved process demonstrated by 35 the use of the apparatus hereinbefore described is carried out as follows:

Assuming that the retorts 4', 4'' and 4 have been charged in sequence and at intervals of equal length in the order stated, the valves 40 5 connecting the transfer pipe 1 and the retorts 4 and 4' are opened immediately following the charging of the retorts 4 and left open during the early stages of the carbonizing period of the retorts 4, one-third of said 45 period, for instance, resulting in a transfer of a part or all of the evolved gas from the retorts 4 to the retorts 4', this transfer of gas being the result of actual pressure difference between retorts 4 and 4', and aided, if desired by the steam jet 8 or other suitable 50 means. A great pressure differential exists between the retorts 4 and 4' and is caused by the high relative production of gas in the retorts 4 during the first stage of the carbonizing period. Likewise immediately following the recharging of the retorts 4', they are put into communication with the retorts 4'' for a like length of time during the early stages of the carbonizing period, resulting in a 55 transfer of a part or all of the evolved gas from the retorts 4' to the retorts 4''. In like manner, a part or all of the gas evolved during the early stages of the carbonizing period in the retorts 4'' is transferred to the retorts 4, this being the condition actually illustrat-

ed in Figure 1, and in which the transfer is shown as being positively aided by means of the action of the steam jet 8'. Of course, if the transfer of the gas in the pipe 1 is downwardly, as, for instance, from retort 4' to 70 retort 4'', and it is desired positively to aid the transfer, then the upper steam jet 8 or any other downwardly-acting transfer-aiding means will be utilized. It will be understood, of course, that the pairs of retorts 75 4-4, 4'-4' and 4''-4'', would not necessarily work together, but that the arrangement of apparatus herein shown is merely suggestive of one practicable way of carrying out the process and that the transfer might 80 be, for instance, from the lower left-hand retort 4'' to the upper right-hand retort 4, or any other relative arrangement, the control of the gas passing through the transfer pipe 1 being such that any two of the retorts 85 may be put into direct communication. By "direct" communication is meant communication without passing through a third or other retorts.

I wish to point out that my improved process and apparatus should not be confused with the well-known practice of steaming an 90 oldest retort without the use of transfer connections or passing water gas previously made through said retort, for the purpose of 95 increasing the yield of permanent gas from said retort, such processes and means being entirely different from my improved process of equalizing the volume and heating value of the gas evolved during the early stages of 100 the carbonizing period with the later parts thereof, and applicable, in the desired degree and with any desired relative arrangement, to all of the retorts of a plant.

The improved results of equalizing the 105 volume and heating quality of gas obtained by the means and process hereinbefore described is also, under the following conditions, realized without the use of transfer connections, the gas offtake and coke offtake 110 being located at the same end of the retort. In the use of a vertical or horizontal retort fed continuously with fresh coal at the end opposite the regular gas offtake end and the coke discharge end, the coke being also discharged continuously, no claim, however, being included in this case to this application of the invention.

If the application of the invention is to 120 retorts which are charged with coal intermittently and a corresponding part of coke is discharged intermittently instead of charging a whole fresh charge of coal and discharging the total coke, as was presumed in the description hereinbefore of the operation 125 of the apparatus shown in Figures 1 and 2, such modified application will be perfectly evident from Figures 1 and 2. The transfer of gas in the early stages of the carbonizing period in sequence from the retorts to that 130

retort in which the coal is most completely carbonized would be effected according to the same practice above described.

Referring in detail to the application shown in Figures 3 and 4, common stop end retorts are indicated by the ordinals 4, 4' and 4² having the annular mouth piece 9, 9' 9² for charging coal and discharging coke. The gas offtakes are indicated by the ordinals 10 10' and 10². The rear wall 13 is penetrated by the iron nipple 11 opening into the clay nipple pipe 12. Packing 14 is provided for securing a gas tight joint. A cross-fitting between the gas conduit 2 and the iron nipple 11 is indicated by the ordinal 15. The gas transfer is effected in the same manner, as previously described as regards the apparatus disclosed in Figures 1 and 2, the actual stage being the same as that shown in said Figures 1 and 2, viz., the transfer of gas from retort 4² to retort 4 during the early carbonizing stage in retort 4².

By the term "retort", it is intended to cover any type of retort, oven or chamber, by whatever name called, in which coal is subjected to dry distillation for the recovery of gas.

What I claim is:

1. In a process of manufacturing coal gas, the steps which comprise, charging in sequence, with coal, a plurality of retorts; initially establishing communication from each freshly charged retort through a second retort containing more completely carbonized fuel to a take off conduit; and subsequently disestablishing the communication between said retorts and delivering gas direct from said first retort to a take off conduit.
2. In a process of manufacturing coal gas, the steps which comprise, charging in sequence, with coal, a plurality of retorts; carbonizing the coal in said retorts simultaneously; passing gas from each freshly charged retort during the early portion of the carbonizing period thereof, through the retort in which the coal is most completely carbonized to a take off conduit; passing all the gas from each retort direct to a take off conduit during the intermediate portion of the carbonization period thereof and passing gas from a freshly charged retort through each retort during the final portion of the carbonization period thereof.
3. In apparatus for manufacturing coal

gas, the combination of a series of retorts; a gas transfer pipe adapted to communicate with each of said retorts; and means for controlling the transfer pipe so that any two of said retorts may be put in direct communication for the transfer of gas from one to the other.

4. In apparatus for manufacturing coal gas, the combination of a series of retorts; a gas transfer pipe positioned adjacently one end of said retort series; gas conduits connecting said retorts, respectively, and said transfer pipe; and independently operated valves disposed in said conduits, respectively; said transfer pipe being adapted to communicate only with said gas conduits.

5. In apparatus for manufacturing coal gas, the combination of a series of retorts provided with a gas offtake at one end; a gas transfer pipe adapted to communicate with each of said retorts at the other end; and means for controlling the transfer pipe so that any two of said retorts may be put in direct communication.

6. In apparatus for manufacturing coal gas, the combination of a series of retorts provided with a gas offtake at one end; a gas transfer pipe positioned adjacently the other end of said retort series and adapted to communicate with each of said retorts at said last-mentioned end; gas conduits connecting said retorts, respectively, and said transfer pipe; and independently operated valves disposed in said conduits, respectively.

7. In apparatus for manufacturing coal gas, the combination of a series of retorts; a gas transfer pipe adapted to communicate with each of said retorts; means for controlling the transfer pipe so that any two of said retorts may be put in direct communication for transfer of gas from one to the other; and steam jets disposed in said transfer pipe for aiding the gas transfer.

8. In apparatus for manufacturing coal gas, the combination of a series of retorts provided with a gas offtake at one end; a gas transfer pipe adapted to communicate with each of said retorts at the other end; means for controlling the transfer pipe so that any two of said retorts may be put in direct communication; and steam jets disposed in said transfer pipe for aiding the gas transfer.

Signed by me, this 4th day of April, 1919.
ALBERT F. KERSTING.
